UNITED STATES PATENT OFFICE.

PAUL BASTIEN AND CHARLES S. CRAWFORD, OF INDIANAPOLIS, INDIANA, ASSIGNEES
TO FREDERIC E. MOSKOVICS, OF INDIANAPOLIS, INDIANA.

DESIGN FOR AN AUTOMOBILE RADIATOR.

Application filed February 13, 1926. Serial No. 16,519. Term of patent 7 years.

To all whom it may concern:

Be it known that we, PAUL BASTIEN and CHARLES S. CRAWFORD, citizens of the United States, residing at Indianapolis, in the county of Marion and State of Indiana, have invented certain new, original, and ornamental Design for an Automobile Radiator, of which the following is a specification, reference being had to the accompanying drawing, forming a part thereof.

Figure 1 is a front elevation and Fig. 2 a

vertical section on the line 2—2 of Fig. 1, of an automobile radiator showing our new design.

We claim:

The ornamental design for an automobile radiator, as shown.

In testimony whereof we affix our signatures.

PAUL BASTIEN.
CHARLES S. CRAWFORD.
